FOREIGN PATENT DOCUMENTS

WO WO-2014023157 A1 * 2/2014 ..... G05D 23/022

Primary Examiner — Ania Aman(74) *Attorney, Agent, or Firm* — Wolf, Greenfield & Sacks, P.C.(57) **CLAIM**

The ornamental design for a thermal bypass valve, as shown and described.

DESCRIPTION

FIG. 1 is a front view of a thermal bypass valve showing our new design;

FIG. 2 is a rear view thereof;

FIG. 3 is a left view thereof;

FIG. 4 is a right view thereof;

FIG. 5 is a bottom view thereof;

FIG. 6 is a top view thereof;

FIG. 7 is a perspective view thereof; and,

FIG. 8 is another perspective view thereof.

The broken lines in the figures represent unclaimed portions of the thermal bypass valve and form no part of the claimed design.

1 Claim, 7 Drawing Sheets(56)
